COMBINED PORTABLE BAR, TABLE AND MAGAZINE RACK

Carlo Hauner, Mompiano, Italy, assignor to Fanini
Fain S.p.A., Aprutina, Italy

Filed Mar. 16, 1973, Ser. No. 341,917

Claims priority, application Italy Sept. 23, 1972

Term of patent 7 years

Int. Cl. D6—04

U.S. Cl. D6—4

FIG. 1

FIG. 2

FIG. 3

FIG. 4

FIG. 5

FIG. 6

FIG. 1 is a perspective view of the combined portable bar, table and magazine rack with the table top in folded, retracted position, the same illustrating my new and ornamental design;

FIG. 2 is a perspective view of said combined portable bar, table and magazine rack with the table top in open, supported position;

FIG. 3 is a front view of the combined portable bar, table and magazine rack with the table top in folded, retracted position;

FIG. 4 is a right side view of the combined portable bar, table and magazine rack with the table top in folded, retracted position;

FIG. 5 is a top plan view of the combined portable bar, table and magazine rack with the table top in folded, retracted position, and

FIG. 6 is a bottom view of the combined portable bar, table and magazine rack.

I claim:

The ornamental design for a combined portable bar, table and magazine rack, substantially as shown.
